UNITED STATES PATENT OFFICE.

JOHN MURTON BROWN, OF IRVINGTON, NEW JERSEY, ASSIGNOR TO CRYSTAL OIL BURNER CORP., OF IRVINGTON, NEW JERSEY, A CORPORATION OF NEW JERSEY.

OIL BURNER.

Application filed July 28, 1924. Serial No. 728,537.

The present invention relates to heat generators and more particularly to a fuel oil burner and is an improvement upon the burner set forth in my copending application Serial Number 696,187, filed March 1, 1924, which matured into Patent No. 1,609,457, December 7, 1926.

An object of the invention is to provide an efficient burner of simple construction and of relatively low cost.

Another object of the invention is to provide a burner which may be quickly and conveniently applied to the ordinary fire box to convert coal or other types of furnaces to the use of a fluid fuel.

Another object of the invention is to provide a burner in which the parts most subject to wear may be quickly and cheaply replaced.

A still further object of the invention is to provide a unit burner having a plurality of nozzles so arranged as to furnish a concentrated heat source effective over the entire area of the water cells of a furnace.

Other objects and advantages of the invention will be apparent as the description proceeds.

In burners of the character to which the present invention relates it is desirable to provide for the distribution of heat in an effective and uniform manner. That is, the burner is adapted for application to a fire pot of a furnace which may have been used to burn coal, it being desirable that the entire area of the water box to be heated which may be relatively large, should preferably be directly in the path of the heat generated by a burner placed in the furnace.

Furthermore, it is desirable to provide a burner having a fire pot which may be quickly adjusted to and properly supported in a furnace and which may be rapidly disassembled and have the parts most subject to wear replaced.

The present invention provides a burner which may be adapted to give a spread of heat waves over substantially the entire area of the water jacket of a furnace to produce steam with comparatively great rapidity.

My invention is also so constructed as to be quickly applied to a furnace without the expense of special fittings or elaborate modification of the furnace and is equally appli-

cable to furnaces of different standard makes and types.

The invention will be more fully understood by referring to the accompanying drawings, in which

Fig. 1 is a plan view of a burner embodying my invention having portions broken away.

Fig. 2 is a sectional view taken on line II—II in Fig. 1 but showing only the burner and firepot structure.

Fig. 3 is an elevational view of the burner shown in Fig. 1.

Fig. 4 is a sectional view taken on line IV—IV in Fig. 3.

Fig. 5 is a plan view of the lower or fire pot portion of the burner with a portion of the nozzle broken away.

Fig. 6 is a sectional view of the nozzle taken on line VI—VI in Fig. 5.

My invention may comprise an upper fuel conduction spider or manifold member 10 and a lower fire pot or multiple arm member 11. The manifold member may include any number of inverted U-shaped fuel conduits 12 as found desirable, having an end of each conduit in communication with the "hot spot" expansion chamber or pocket 13, four arms being shown in the present embodiment of the invention. The fire pot 11 in the present instance is also provided with four channels or arms 14 in corresponding arrangement to the conduits 12. Each of the arms 14 may have a longitudinal cavity or trough 15 having the bottom portions 16 semi-circular in transverse cross section and adapted to receive a removable nozzle member 17. The troughs may be arranged to communicate at their inner ends to provide a cross-shaped or cruciform crater having the intersection portion of the troughs disposed beneath the expansion chamber 13.

The member 17 includes four radial projections 18 which may also be of semicircular form in transverse cross section and adapted to cooperate with the semi-circular portions 16 to provide passageways 19 for the fuel. The member 17 may be provided with five rows of apertures 21 spaced at intervals along the member and in sufficient number to discharge a predetermined amount of fuel. The lower row of apertures are so disposed with respect to the fire-brick, subsequently

described, as to maintain them heated and thus prevent the burner from being rendered inoperative. The intermediate row of apertures are drilled at such an angle with respect to the upper edge of the fire brick that the flame emerging therefrom does not strike the same but is directed outwardly beyond the conduits 12 and into the firebox and against the water cells. Openings 21 are provided in the ends of the arms 14 and are so drilled that the flame therefrom impinges upon the firebrick located at the ends of the arms 14. A large opening 21" is disposed at the center of the member 17 so that the flame therefrom is directed against the hot spot chamber 13.

The member 17 may be provided with flange portions 22 adapted to rest upon seats or ledges 23 in the troughs 15. Bolts 24 extending through the flanges 22 and the ledges 23 may be employed to removably attach the nozzle member 17 to the burner.

Each of the arms 14 of the fire pot may terminate in a tubular portion 24' having an external flange 25 adapted to be connected by suitable bolts 26 to a companion flange 27 at an end of a conduit 12.

Thus communication is afforded between the expansion chamber and the burner nozzle 17 through which fuel may issue for ignition. Each of the trough-shaped portions 15 may be provided with removable fire brick linings or side walls 27' having their inner surfaces 28 sloping upwardly in an arc from the troughs to provide flaring apertures for the distribution of heat waves.

When the upper fuel conducting manifold 10 is in place and secured by bolts 26 to the fire pot 11, fuel entering the pocket 13 will first be subjected to an intense heat and "cracked" and the gases thus formed guided through the conduits 12 to the nozzle plate or member 17 for ignition.

Fuel may be led to the pocket 13 by means of a pipe 29 connected with a fuel source (not shown) of any suitable character. Any desirable fluid fuel may be used, the present construction of burner being, however, more particularly adapted for use with a fuel mixture of the character set forth in the above-mentioned copending application which as therein stated is a mixture of a heavy oil and air in an atomized state and propelled at a relatively high velocity against a "hot spot".

This mixture is led through pipe 29 to a spout or discharge nozzle 31 so disposed within the chamber 13 as to discharge the mixed fuel against the downwardly extending curved portion 32 of the pocket 13, which portion is disposed directly in the path of the heat waves emanating from the fire pot, thereby attaining a very high temperature. It is to be noted that the downwardly extending portion 32 of the pocket 13 is dis-

posed considerably nearer the burner nozzles than the conduits 12, whereby the portion 32 attains a higher temperature than the conduits, although the latter are maintained at a sufficiently high temperature to prevent the gases formed within the chamber 13 from condensing.

The portion 32 is termed the "hot spot" of the burner and when the mixture is projected thereagainst it is broken up or "cracked" and divided into its more volatile constituents and thus converted into a highly gaseous state so that when discharged from the burner nozzle 17 a substantially complete combustion is attained and no objectionable or deleterious carbon deposits upon the furnace walls result. The highly active state of the gases generated in the pocket due to the hot spot leave the passages free from becoming clogged with solid residues. It has been found that only after long and severe use it may be found necessary to brush off the walls of the conduits. For this purpose threaded plugs 33 may be provided to permit access to the conduits when desirable.

The spout or discharge nozzle 31 may be provided with a flange 34 having arcuate slots 35 for the passage of tap bolts 36 into threaded holes in a seat 37 integral with and common to the several conduits 12. By reason of the slotted flange 34, an elbow portion 37 of the discharge nozzle 31 may be adjusted about a central axis of the burner thus imparting flexibility to the structure and facilitating installation. It will be appreciated that the discharge nozzle may easily be removed and the pocket inspected when desirable; or nozzles of different outlet area may be substituted one for another if it is desirable to vary the volume and velocity of the mixture discharged against the hot spot.

The burner nozzle comprising the perforated member 17 is obviously subjected to the most wear and may be made of any hard material such as Monel metal or the perforations may be provided with peripheral reinforcements of such metal or other heat resistant substance. By virtue of the present construction, the nozzle member may, however, be quickly and cheaply replaced without the necessity of disassembling the other elements of the burner.

The present invention therefore contemplates a burner of such construction as to meet favor for domestic use as well as for use in connection with high pressure heating or other systems. The simplicity of the fire pot and its adaptability to meet a great variety of conditions has demonstrated the fact that it is a decided advance step in the art of fuel heating units.

Although a preferred embodiment of my burner has been illustrated and described, it is to be appreciated that persons skilled in

the art may make modifications therein, but such modifications as come within the terms of the appended claims are contemplated by me as falling within the spirit and scope of my invention.

What I claim is:

1. A fluid fuel burner comprising a manifold for guiding fuel in a plurality of paths, a fire pot consisting of intersecting channels, said manifold and fire pot being in communication, and a removable nozzle member positioned in said channels.

2. A fluid fuel burner comprising a pocket, means for feeding fuel to said pocket, a fire pot consisting of intersecting troughs and communicating conduits between said pocket and said fire pot.

3. A fluid fuel burner comprising an expansion chamber, a fuel ignition chamber having a plurality of channels intersecting at a common point, said channels being divided transversely to provide a removable upper section, and a removable nozzle member for discharging fuel in said channels.

4. A fluid fuel burner comprising an expansion chamber, a fuel ignition chamber comprising a plurality of intersecting channels consisting of an upper and lower section and a nozzle member adapted to be positioned in communication with said channels.

5. An oil burner comprising a plurality of inverted substantially U-shaped supply conduits and a cruciform fire pot connected thereto.

6. An oil burner comprising a plurality of inverted substantially U-shaped intersecting supply conduits, a downwardly extending chamber disposed at the intersection of said conduits, and a fire pot connected to said conduits and so disposed with respect to said chamber as to intensively heat the same when the burner is in operation.

7. An oil burner comprising a plurality of intersecting conduits, a downwardly pro-

jecting chamber disposed at the intersection of said conduits, and a cruciform fire pot connected to said conduits.

8. An oil burner comprising a plurality of intersecting conduits, a fuel supply nozzle entering said conduits at the intersection thereof, and a cruciform fire pot connected to said conduits.

9. An oil burner comprising a central chamber, a plurality of conduits having portions thereof extending outwardly and upwardly and then downwardly from said chamber, a supply conduit angularly adjustable connected to said chamber, and a fire pot connected to said conduits.

10. An oil burner comprising a plurality of outwardly and downwardly extending conduits intersecting one another to form a central chamber, a cruciform fire pot connected to said conduits, a heat resistant lining for said fire pot adjacent its sides and burner openings in said fire pot some of which are adapted to maintain said lining heated, others of which are so disposed as to project a flame in line with the upper edge of said lining and others of which are so disposed as to direct a flame vertically with a portion thereof adapted to heat said central chamber to a high temperature.

11. An oil burner comprising a plurality of supply conduits, a cruciform fire pot connected to said conduits and removable fire brick within said fire pot to form a lining therefor.

12. An oil burner comprising a plurality of supply conduits, a cruciform fire pot connected to said conduits, and a removable fire brick lining for said fire pot, said fire brick having flaring faces.

In testimony whereof, I have hereunto subscribed my name this 24th day of July, 1924.

JOHN MURTON BROWN.
